UNITED STATES PATENT OFFICE.

FRANK N. KEITHLEY, OF BURLINGAME, CALIFORNIA, ASSIGNOR TO METAL & THERMIT CORPORATION, OF CHROME, NEW JERSEY, A CORPORATION OF NEW JERSEY.

MOLD FOR WELDING RAILS AND THE LIKE.

Application filed January 17, 1923. Serial No. 613,194.

To all whom it may concern:

Be it known that I, FRANK N. KEITHLEY, a citizen of the United States, and a resident of Burlingame, in the county of San Mateo and State of California, have invented certain new and useful Improvements in Molds for Welding Rails and the like; and I do hereby declare the following to be a full, clear, and exact description of the invention, such as will enable others skilled in the art to which it appertains to make and use the same.

This invention relates to improvements in molds for welding the ends of rails and the like by means of superheated molten metal, such as thermit steel, or superheated steel produced in the electric furnace, the object of the invention being to provide a mold with an arrangement of pouring gates that will ensure the distribution of the superheated metal to the mold cavity adjacent opposite sides of the rails, more particularly the opposite sides of the head sections. As heretofore practiced, it has been customary to provide molds of this character with a single pouring gate so that the rail sections adjacent the gate were unduly heated and the molten metal flowing toward the sections remote from the gate was unduly chilled, which resulted in a defective and unsatisfactory joint. The present invention overcomes the objections to the former types of mold by providing a mold with a basin or reservoir on its top to receive the superheated molten metal, and two pouring gates connecting the bottom of the basin with the mold cavity, the gates being so positioned as to deliver separate streams of the molten metal into the mold cavity adjacent opposite sides of the head section of the rail, so that the two streams of hot unchilled metal pass directly to both sides of the rail heads and effect a thoroughly sound weld at these points with a minimum use of molten metal.

The invention is illustrated in the accompanying drawings, in which,

Fig. 1 is a sectional elevation of the ends of two girder rails with a mold embodying my invention applied thereto, the section being taken on the line 1—1 of Fig. 2.

Fig. 2 is a section taken on the line 2—2 of Fig. 1.

Fig. 3 is a plan view of the mold and rail ends.

In the drawings, 1 indicates the mold,

which is made of sand or other refractory material, adapted to be placed about the adjacent ends of the rails A, B, which are of the girder type, and arranged with the ends of the rails separated by an intervening vertical space 10. The upper portion of the mold 1 is provided with a recess 2 constituting a basin or reservoir into which the superheated welding metal is poured, and connecting the bottom of this basin 2 with the joint defining space or cavity between and about the rail ends are two pouring gates 3 and 4, the basin connecting with these gates through channels 5, 5, which serve as runners through which the molten metal flows simultaneously to the opposite gates.

The gate 3 is conveniently located in vertical alignment with the space 10 between the rail ends, and above the lip section of the girder rail, so that the metal entering by way of said gate 3 will pass downward between the ends of the rails through sections 11 and 12 of the mold cavity and settle quietly in the bottom of the latter in the space 13 surrounding the bases of the rail ends. The pouring gate 4 is preferably located above the outside edges of the rail ends, and in alignment with the space 10, so that the first portions of the pour entering by gate 4 pass downward through sections 14 and 15 of the mold cavity and join the corresponding portions of the pour entering by gate 3 at the bottom 13 of the mold cavity. As the molten metal rises in the mold cavity, the successive increments supplied simultaneously by the gates 3 and 4 pass directly to their ultimate positions in the cast joint without being forced to flow or wash across the faces of the rail ends. In this way no portion of the molten metal is unduly chilled.

The advantage of this arrangement will be manifest when it is considered that, according to the customary practice, all of the hot molten steel entering through a single pouring gate located at one side of the rail head results in an excessive melting of the rails adjacent the point of entrance, and a consequent undue cooling or chilling of the first portions of the pour of the molten metal. Furthermore, according to the old practice, the last portion of the molten metal entering the mold by a single gate was caused to flow completely across and be-

2
tween the rail heads, so that the part of the molten metal which finally reposed adjacent the remote section of the rail head was unduly cooled and chilled, with a resultant 5 weak or defective joint due to a non-uniform welding action and irregular expansion and contraction. To partially overcome this difficulty, it was found necessary to use an excess of molten metal, which was 10 largely wasted. All of these difficulties are overcome by the present method.

While my improved mold is here shown as applied to the welding of rails of the girder type only, it will be understood that 15 it is equally effective in producing sound and satisfactory welds between the ends of T-rails and other similar metallic shapes of irregular cross-section.

What I claim is:

20 1. Means for welding rails and the like by means of superheated fluid metal, com-

prising a mold of refractory material having a joint defining cavity surrounding the rail ends, a basin in the top of the mold, and spaced pouring gates connecting the 25 bottom of the basin with the top of said cavity to direct the entering metal to both sides of the rails simultaneously.

2. Means for welding rails and the like by means of superheated fluid metal, comprising a mold of refractory material having a joint defining cavity surrounding the rail ends, a basin in the top of the mold, a 30 pouring gate connecting the basin with the mold cavity adjacent the gauge side of the 35 rails, and a second gate connecting the basin and the cavity adjacent the opposite side of the rails; whereby the molten metal will be caused to flow to both sides of the rail simultaneously.

In testimony whereof I affix my signature.
F. N. KEITHLEY.
